GEORGE H. BARLOW AND J. J. DESMOND, OF CORRY, PENNSYLVANIA.

WIRE-BENDING MACHINE.

977,515.

Specification of Letters Patent.

Patented Dec. 6, 1910.

Application filed January 16, 1908. Serial No. 411,063.

To all whom it may concern:

Be it known that I, JOHN R. DEAN, a citizen of the United States, residing at Girard, in the county of Erie and State of Pennsylvania, have invented new and useful Improvements in Wire-Bending Machines, of which the following is a specification.

This invention relates to wire bending machines and consists in certain improvements in the construction thereof as will be hereinafter fully described and pointed out in the claims.

The machine may be used for forming various articles, but the invention as specifically exemplified by the drawings is particularly adapted to forming stays for corsets and the like, and as shown is arranged to form a stay similar to that shown in my Patent No. 868,763, issued Oct. 22nd, 1907. The machine, however, without material alteration is adapted to form numerous shapes and forms of fabrics.

The machine is illustrated in the accompanying drawings as follows:

Figure 1 shows a side elevation of the machine. Fig. 2 a section on the line 2—2 in Fig. 1. Fig. 3 an end elevation of the coil forming mechanism. Fig. 4 a top view of the hammer operating levers. Fig. 5 a plan view partly in section of the lengthening device. Fig. 6 a section on the line 6—6 in Fig. 5. Fig. 7 an end view of the lengthening device. Fig. 8 an end elevation of the flattening hammer. Fig. 9 a central section through the bobbin. Fig. 10 an elevation of the end of the tensioning guide. Fig. 11 is an end elevation of the lower end of the forming hammer and its anvil. Fig. 12 is a plan view of the fabric formed by the machine.

The machine as shown is supported by a wooden frame having the corner uprights 1 and 2 at one end, and the opposite end (not shown) of substantially similar construction. The driving shaft 5 is journaled in a box 4, the box being carried by the cross piece on the end of the frame as shown in dotted lines in Fig. 2. The opposite end of the shaft is journaled on the frame in any convenient manner (not shown). The drive shaft 5 is driven by pulley 6.

The side pieces 7 extend lengthwise of the frame, and the uprights 9 are secured to these side pieces intermediate thereof. A guide plate 10 is secured between the up-

rights 9 (see Fig. 3). This guide plate has the openings 11 and 12 which are connected. The outer edge of these openings forms an edge of the bobbin guide-ways 22 and 23. The shafts 13 and 14 are secured on the cross piece 3 by means of the clamping block 15 (see Fig. 2), these shafts extending lengthwise of the machine through the openings 11 and 12 in the plate 10. A bracket 16 is secured to the back of the plate 10, and carries a cross piece 17. This cross piece has openings through it, and the shafts 13 and 14 extend through these openings, the openings being somewhat larger than the shafts, and flanges 18 extend from the cross piece 17 around the openings. Set-screws 19 extend through the flanges against the shaft and form a means for adjusting the shaft. The guide plates 20 and 21 are fastened on the front ends of the shafts 13 and 14, and are so shaped relatively to the openings 11 and 12 as to form race ways 22 and 23 for the bobbins.

It will be seen that the adjustment of the shafts 13 and 14 by the set screws 19 affords means for so positioning the plates 20 and 21, as to give the race ways a uniform width throughout. These race ways cross at the point 24, and immediately adjacent to these points are the pin holding plates 25 and 27, on which are arranged the coil forming pins 26 and 28. The plates 25 and 27 have the slots 29, and they are secured to the plates 20 and 21 by screws 30 extending through these slots. By moving the plates 25 and 27 on the screws, the distance between the pins 26 and 28 may be varied so as to vary the width of the material.

The shuttles 31 are driven in the race ways 22 and 23. Deflectors or guides 32 are arranged on the faces of the plates 20 and 21, and these with the guides 33 extending from the plates 25 and 27 carry the wire over the faces of the plates 25 and 27. It will be noted, however, that the bobbins are at the rear of the plane of the plates 25 and 27, so that the wire is drawn tightly against the plates 25 and 27, and thus each coil is drawn in back of the preceding coil, so as to force this preceding coil outwardly on the pins, and in this way permit of a continuous formation of the coils. The position of the wire 34 is shown in Fig. 3. The shuttle is shown in detail in Fig. 9.

Wire is wound on spools 35. These spools

are journaled on the pins 36. A cover 35^a is provided for the spool to prevent the springing out of the wire. The pin 36 is fixed in a frame 37. The projections 38 extend from 5 the frame 37, and the roller 39 is journaled between these projections on the pin 39^a. A plate 40 is also secured to the frame, and when the shuttle is in place it is in contact with the rear surface of the plates 10, 20, 21 10 at the edges of the race ways. A plate 41 (see Figs. 3 and 9) contacts the surfaces on the front faces of the same plates adjacent to the race ways. The plates 40 and 41 are of somewhat greater width than the race- 15 ways, so that the shuttles are held in place by them. Distance pieces 42 are secured between the plates, and these are of such length relatively to the thickness of the plates 10, 20 and 21 as to permit the plates 40 and 41 20 to move freely on the faces of the plates. Rollers 43 are journaled between the plates, and are of such diameter relatively to the distance pieces as to engage the surfaces of the race-ways and relieve friction. The wire 25 extends from the spool through the openings 44 in the plates 40 and 41 under the tension plate 45 through the guide 46 to the coil forming pins. The guide 46 has the extension 47 secured to the plate 41. A screw 48 30 extends from this extension and adjustment nut 49 is arranged on the screw, so that the tension may be varied. The guide 46 has the rounded surface, as clearly shown in Fig. 10, over which the wire runs as it extends 35 laterally from the shuttle when put under strain as shown in Fig. 3. It will be noted that the wire runs slack except as the shuttles pass the extreme portion of the race way (position shown in Fig. 3). Here the strain 40 on the wire is sufficient to give the coils some set.

The shuttles may be variously driven so as to form different fabrics, and if desired a single shuttle may be used forming a single 45 wire fabric. As before stated the machine as shown is arranged to form a fabric similar to that shown in Fig. 12. It will be noted that the coils of this fabric are interlocked at 125 and overlapped at 126. To 50 form this fabric the shuttles must traverse one of the race-ways, and return so as to lay its wire directly upon itself, and the wire of the other shuttle passes from one coil to another by its action in the opposite race way. 55 As shown in Fig. 3 the mechanism driving the shuttle of the race way 22 is speeded exactly twice that of the shuttle in the race way 23.

For convenience of description I will designate the shuttle 31 in the race-way 22 (see 60 Fig. 3) as the first shuttle, and the shuttle 31 in the race-way 23 as the second shuttle. Starting with the position shown in Fig. 3, the first shuttle will be driven out of the 65 race way 22 into the part 23^a of the race-way

23, by the time the second shuttle reaches the top of the race way 23, that is, the first shuttle traveling in the race way 22 twice as fast as the shuttle in the race way 23 will travel the half revolution, while the second shuttle 70 is traveling one fourth of the revolution. The first shuttle remains in the part 23^a disengaged by any driving mechanism until the second shuttle has been driven out of the race way 23 into the race way 22, when the driving mechanism which has been operating upon the second shuttle picks up the first shuttle by its continued movement and forces it along the race way 23. This second shuttle will then be driven around the race way 80 22, and into the part 23^a of the race way 23 before the first shuttle has completed its travel through the race way 23, and the wire carried by this second shuttle will cross itself 85 in contact as the shuttle passes from the race way 22 to the race way 23, and this is true in each instance with relation to the wire carried by a shuttle traversing the race way 22. The wire carried by the shuttle in the race way 23 passes from one loop to another 90 as the shuttle passes from the race way 22 to the race way 23, the wire at this crossing not being in contact with itself, but in contact with the preceding loop. By thus varying the relation of loops, that is, crossing the wire in contact as the shuttle moves from the race way 22 to the race way 23, and jumping from one loop to the next when the shuttle passes from the race way 23 to the race way 22, such a relation is given to the loops one 95 to the other, that the wire when flattened out forms the interlock at one side as shown at 125 in Fig. 12, and the overlap as shown at 126 in said figure. It will be understood, however that generically considered, this specific relation of the loops may be varied depending on the timing and speeding of the driving mechanism acting on the shuttles in the race ways. It will be noted that the axis 100 of the coils formed on the pins is at right angles to the plane in which the shuttles travel, and that the fabric as it is forced off the pins is in the form of a series of figure 8 coils in close contact whose axes are lengthwise of the fabric. 110

The driving mechanism for the shuttle is as follows: Gear 50 is journaled on the shaft 14 and is driven by gear 51 on the driving shaft 5. The gear 50 drives the gear 52 which is journaled on the shaft 18. A 120 driver 53 is fixed on the gear 52, and is shaped to engage the roller 39 on the shuttle, and to drive the shuttle through this engagement. A similar driver 54 is fixed on the gear 50. The driver 53 drives the shuttle through the race way 22, and the driver 54 through the race way 23 and these drivers are simply arms carried on the hubs of the gears 50 and 52, and are of such length that their ends will engage the rollers 39 on the 130

shuttles throughout the length of the race ways. The drivers are disengaged from the shuttles, and the shuttles jump from one race way to the other when the shuttles reach the point 24. This free movement or overrunning of the shuttles is facilitated by the fact that it is always in a downward direction, so that it is assisted by gravity as well as the momentum of the shuttle. The driver 10 53 alternately drives a bobbin one revolution and runs idle one revolution, so that although the driver 53 travels twice as fast as the driver 54, a shuttle is made to traverse the race way 22 only with every other revolution. As each succeeding coil is made, the wire forming it is drawn in back of the preceding coil, so as to force the fabric made up of the preceding coils off from the pins 26 and 28. It then moves into a guide way, the bottom of which forms an anvil 55 for the hammer 58. (See Fig. 8). The guide way is provided with a stationary side 56 and a movable side 57. The movable side is formed by the front face of a slide plate 59. The rear end 20 25 of this plate is guided by the pins 60 and the front of the slide rests on the anvil, and is secured by the screw 61 which extends through the slot 62. The hammer is carried by a plate 58^a and this plate extends through 30 a bracket 63, and is thus guided. The hammer plate 58^a is pivotally connected with a lever 64, which lever 64 is pivotally supported by the pin 65 on the bracket 66 extending from the plate 10 (see Fig. 4). An eccentric rod 68 is pivotally secured to the lever 64 by means of a pin 67. The rod terminates in an eccentric strap 69 which operates upon the eccentric 70. The eccentric 70 is fixed on the driving shaft 5. With each revolution of the driving shaft, therefore, the hammer is depressed and engages and flattens the coils formed on the pins. Following the operation of this mechanism, the eccentric 70 on the drive shaft reciprocates the 40 45 link 68. (See Fig. 1). The link 68 or connecting rod is pivotally connected by means of the bolt 67 with the lever 64 and through the connection reciprocates the lever 64. The hammer plate 58^a and consequently the 50 55 hammer is reciprocated with the lever 64, (see Figs. 4 and 1). It will be noted that the flattening process changes the axis of the coils from a direction lengthwise of the fabric to a direction approaching a right angle to the general plane of the fabric.

It is desirable that the sides of the fabric be engaged as it is depressed or flattened so that the edges of the resulting fabric may be straight. To accomplish this a bracket 71 is secured to the hammer plate 58^a. A rod 72 extends through this bracket and adjusting nuts 73 are arranged above and below it so that the rod may be adjusted. The bell-crank lever 74 is pivoted on the bracket 76. 60 65 The bracket 76 is formed by a projection

from the bracket 77, and the bracket 77 is secured to and extends forwardly from the plate 10. The upper arm of the bell-crank lever extends through a perforation 81 (see Fig. 2). It will be readily seen that as the hammer descends the side 57 is pushed inwardly through the action of the bell-crank lever. The fabric in this stage of its development will have its coils close together in longitudinal direction, and for most fabrics 75 it is desirable to lengthen it. A device for this is shown in detail in Figs. 5, 6 and 7. It is in position to receive the fabric as it comes from the flattening hammer, and just as the fabric is engaged by the hammer, and 80 lengthens or stretches it while the fabric is in the grip of the hammer. This lengthening mechanism and the succeeding mechanisms co-operating on the fabric are supported by a plate 78 which extends longitudinally of the machine. One end of this plate is supported by a bracket 77, and the other in any convenient manner not shown. A guide plate 82 is bent around the plate 78, the sides being brought up and having an 90 inwardly extending edge 83. A slide 84 moves in the guide thus formed. It is provided with a slot 85 through which the fabric passes. The clamping finger 86 is pivoted on the block 84 by means of a pin 88. 95 The clamping finger has preferably a leather face 87, so that it may more readily grip the fabric. An arm 89 forms a bell-crank with the finger, and extends through the slots 90 and 91 in the plates 78 and 82.

100 A strap 97 is pivotally secured to the end of the arm 96 by a pin 98 and the eccentric rod 99 is pivotally secured to the strap 97 by the pin 100. The rod 99 terminates in an eccentric strap which is operated upon 105 by the eccentric 101. This eccentric is so timed with relation to the eccentric 70 that the arm 93 is moved toward the left as shown in Fig. 1, so as to move the block 84, and the finger 86 forward while the hammer 110 is up, and this action is reversed so that the wire is gripped by the finger just as the wire has been fully engaged and gripped by the flattening hammer. A further movement toward the right by the arm 93 throws the 115 arm 89 and with it the block 84 and finger 86 toward the right, and this carries with it the fabric, and thus lengthens it. This lengthening device works with great accuracy with relation to the number of coils, 120 so that the distance between one coil and another is very uniform.

125 After the fabric passes from the lengthening device it has, when treated as shown, a tendency to roll up. The reason for this is that the machine, as it coils the wire on the pin 26, twists that part of the wire forming the transverse portions of the coil, and twists all these portions so that they tend to curl the fabric in the same direction. Observing 130

Fig. 3 it will be noted that the span of wire from the shuttles to the pins is brought to tension at the under side of the pins in each instance. As this occurs, the wire forming the span is forced between the blades 25 and 27, and the bottom of the preceding coil, thus forcing the bottom of the preceding coil outwardly, and this twists the transverse portion extending from the bottom of this coil. There would, of course, be a neutralizing twist in the transverse portion extending from the top of the same coil were it not for the fact that this transverse portion continues to the shuttle, so that this long span of wire takes up the twist without appreciably affecting the transverse portion. In each instance, therefore, the bottom of the coil being forced outwardly, the transverse portion is twisted so as to give the resulting fabric a tendency to curl upwardly or toward the top. If the direction of movement of the shuttles were forced so that the tension on the span of wire would be taken up at the top instead of at the bottom, this tendency would of course be reversed.

The torsional elastic limit of wire is increased by giving it an initial twist beyond its elastic limit. For example, if a wire is twisted slightly beyond its elastic limit, it will be found that its torsional elastic limit in the direction that it has been twisted has been increased, while its torsional elastic limit in the opposite direction is decreased. For some uses stays are subjected to very sharp bends in one direction so that it is very desirable to have them able to stand these bends without taking a permanent set, while at the same time, flexure in the opposite direction is not so great. Where this is the case, giving to the stay an initial twist in the transverse portion, thus increasing its resistance to a permanent set in that direction, is therefore desirable. The present machine is capable of doing this, not only with a single wire but of coiling a fabric with this initial twist and at the same time associating a plurality of wires. Of course, as the stay is forced off of the coiling pins, it has a tendency to curl up. To avoid this I have provided a forming hammer. The anvil 102 of this forming hammer is carried by the plate 78 and is convex longitudinally of the plate, that is, has its axis across the fabric and parallel to its plane. The hammer 103 (see Figs. 1 and 11) is similarly faced, so that the fabric is given a set in a direction reverse to that in which it has a tendency to coil, and the result is that the fabric after passing the forming hammer will normally lie in alinement. The hammer is carried by the hammer plate 104, and this plate extends through a guide formed by an extension 105, on the bracket 63 and also

extends through a guide 106. This guide 65 is supported by a cross piece 107 extending across the machine. (See Figs. 1 and 4). A lever 108 is pivotally secured by means of a pin 111 on a lug 110 extending from the bar 107. The pin 67 extends through the end of the lever 108 so that the lever is operated by the eccentric 70. It will be noted, however, that the lever 108 is fulcrumed intermediate of its ends, while the lever 74 is fulcrumed at its end, so that the hammers 103 and 58 alternate in their movement. In this way the hammer 103 is in its upper position as the fabric is pulled out by the lengthening device.

It is also desirable with some fabrics to form one face concave in a crosswise direction, and this can be accomplished by shaping the faces of the anvil 102 and hammer 103 as shown, and these faces are not only curved longitudinally, but also laterally for this purpose. This lateral curving of the face of the anvil and hammer is clearly shown in Fig. 11.

The fabric after leaving the hammer 103 passes through a guide 112, and then between the rolls 113 and 114. These rolls are so driven as to keep the fabric under tension. The wheel 114 is journaled on a shaft 116, and this shaft 116 is slidingly mounted on the pins 117. The pins extend upwardly from the plates 78. Springs 118 are tensioned against the shaft 116 and nuts 119 are screwed onto the pins 117, so as to vary the tension as desired. A wheel 120 is fixed on the shaft 115 and is intermittently driven forward as the machine operates. A link 121 is pivotally secured to the hammer plate 104. It is pivotally connected with a block 122, and the block 122 is pivotally mounted on the arm 123, the arm being journaled on the shaft 115. The block 122 is so shaped relatively to the wheel 120 as to engage it as the rod 121 is pulled upwardly, and thus carry the wheel 120 with it, and on the downward stroke of the hammer, the block 122 releases the wheel 120 and permits the block to move over the surface, so as to engage a new surface on the wheel and thus intermittently advance the wheel.

What I claim as new is:

1. In a wire bending machine, the combination of devices for forming coils with their axes lengthwise of the fabric; a guide way into which the fabric is forced from the devices, said guide way engaging the side of the fabric and confining the same; and mechanism engaging and bending the coils in the guide way to flatten the fabric.

2. In a wire bending machine, the combination of devices for forming coils with their axes lengthwise of the fabric; a guide way into which the fabric is forced from the devices, said guide way engaging the

- sides of the fabric and confining the same; and mechanism acting intermittently upon the fabric for bending the coils and flattening the fabric.
5. 3. In a wire bending machine, the combination of devices for forming continuous coils with the axes of the coils lengthwise of the fabric, each succeeding coil forcing the preceding coil from the device; a guide way 10 into which the coil is forced, said guide way engaging the sides of the fabric, and confining the same; and a flattening device acting upon the coils in the guide way.
4. In a wire bending machine, the combination of devices for forming continuous coils with their axes lengthwise of the fabric; a guide way into which the coil is forced from the devices; means for contracting the guide way; and means for flattening the 20 coil as the guide way is contracted.
5. In a wire bending machine, the combination of devices for forming continuous coils with their axes lengthwise of the fabric; a guide way into which the coil is forced 25 from the devices; and means for contracting the guide way and intermittently engaging the coil.
6. In a wire bending machine, the combination of devices for forming coils; a guide-way 30 into which the coils are forced; means for reciprocating one side of the guide way to contract the guide way; and a hammer acting on the coils in the guide way, said hammer engaging the coil as the guide-way 35 is contracted.
7. In a wire bending machine, the combination of coil forming devices; a guide way into which the coil is forced; means for reciprocating one side of the guide to contract 40 the guide-way; a hammer acting upon the coil within the guideway; and mechanism connecting said means with the hammer whereby the side of the guideway and the hammer reciprocate in unison.
45. 8. In a wire bending machine, the combination of mechanism for continuously forming a fabric of flat coils; a reciprocating gripping mechanism; a means actuating the gripping mechanism to grip the fabric and 50 carry the fabric with it to move it in one direction to lengthen the fabric, and to release the fabric and return thereon when the gripping mechanism is moved in the opposite direction.
55. 9. In a wire bending machine, the combination of mechanism for continuously forming a fabric of flat coils; a gripping mechanism comprising a sliding block; a clamping finger carried by the block; an arm extending 60 from the finger and forming a bell-crank lever therewith; a means for reciprocating the arm whereby the clamping finger is released and the block returned with the movement of the arm in one direction; and 65 the clamping finger engaged and the block
- and clamping finger moved with a movement of the arm in the opposite direction to lengthen the fabric.
10. In a wire bending machine, the combination of mechanism for continuously forming a fabric of flat coils comprising a hammer by which the coils are engaged and flattened by a reciprocating movement of the hammer; and a reciprocating gripping device adapted to engage and move the fabric 70 as the fabric is engaged and held by the hammer.
11. In a wire bending machine, the combination of devices for forming coils with their axes lengthwise of the resulting fabric; a flattening device acting upon the coils so formed; and a hammer with a curved face, the axes of the curve being across the fabric and parallel thereto for giving the fabric a set in a reverse direction from the natural 75 tendency of the coil.
12. In a wire bending machine, the combination of devices for forming coils with their axes lengthwise of the resulting fabric; a hammer acting upon the coils so formed 80 for flattening the same; and a second hammer with a curved face, the axes of the curve being across the fabric and parallel thereto for giving to the fabric a set in a reverse direction from the natural 85 tendency of the coil.
13. In a wire bending machine, the combination of a coil forming device; a hammer for flattening the coil; a reciprocating lengthening device operating with relation 90 to said hammer to engage and lengthen the fabric as the fabric is engaged and held by the said hammer; and a second hammer operating upon the fabric, said hammers being alternately timed to engage the fabric 95 alternately.
14. In a wire bending machine, the combination of a coil forming device; a hammer for flattening the coil; a second hammer having a curved face for setting the 100 fabric flattened by the first mentioned hammer; and means for operating said hammers alternately.
15. In a wire bending machine, the combination of coil forming devices; a first 110 hammer for flattening the coil; a second hammer for setting the fabric, levers 64 and 108 for operating said hammers respectively, one of said levers engaging the hammer between its actuated end and its fulcrum, and the other of said levers having its fulcrum between its end and its point of engagement with the hammer, whereby said hammers are operated alternately; and fulcrum supports for said levers.
16. In a wire bending machine, the combination of devices for forming coils with their axes lengthwise of the resulting fabric; a hammer to which the coils pass from 115 said device for flattening the coils; and a 120

1. In a wire bending machine, the combination of two coil forming pins; and means acting with the pins for forming interlocking figure 8 coils on said pins with their axes lengthwise of the fabric. 70

2. In a wire bending machine, the combination of two coil forming pins; and means acting with the pins for forming interlocking figure 8 coils with a plurality of wires on said pins. 75

3. In a wire bending machine, the combination of two coil forming pins; and means acting with the pins for forming interlocking figure 8 coils with a plurality of wires on said pins and with the axes of the coils lengthwise of the resulting fabric. 80

4. In a wire bending machine, the combination of two coil forming pins; and means acting with the pins for coiling a plurality of figure 8 coils on said pins with a plurality of wires and with the wires crossing alternately upon themselves. 85

5. In a wire bending machine, the combination of two coil forming pins; guide ways; a plurality of shuttles arranged to lead wires over said pins; and means for actuating said shuttles relatively to each other to interlock the coils. 90

6. In a wire bending machine, the combination of a coil forming mandrel; shuttle guides arranged to form coils in relation thereto; a plurality of shuttles operating in said guides; and means for actuating said shuttles relatively to each other to interlock coils formed by the wires from said shuttles 95 on said mandrel. 100

7. In a wire bending machine, the combination of two coil forming pins; figure 8 guide ways arranged in relation to said pins to form figure 8 coils; and a shuttle in said 105 guide way.

8. In a wire bending machine, the combination of two coil forming pins; figure 8 guide ways arranged in relation to said pins to form figure 8 coils; and a plurality of 110 shuttles in said guide ways.

9. In a wire bending machine, the combination of a guide plate having a shuttle guide way therein; a coil forming pin; a plate holding said pin, the plate holding said 115 pin being out of the plane of the guide ways; a shuttle in the guide way; and means for deflecting a wire carried by the shuttle to the pin, so as to form coils on the pin as the shuttle traverses the guide way in close contact with the pin carrying the plate whereby a preceding coil is forced outwardly on the pin by each succeeding coil as it is formed. 120

10. In a wire bending machine, the combination of two pins; pin plates 25 and 27 carrying said pins; a guide-way plate having a guide way therein, said guide way being out of the plane of the pin plates and having the form of a figure 8; a shuttle in said guide way; and deflecting devices for 125

11. In a wire bending machine, the combination of two coil forming pins; and means acting with the pins for forming interlocking figure 8 coils on said pins. 130

guiding a wire carried by the shuttle to the base of the pin.

36. In a wire bending device, the combination of two coil forming pins; a figure-8 5 guide-way arranged in relation to said pins; a plurality of shuttles in said guide way adapted to coil a plurality of wires on said pins as the shuttles traverse said guide way; and drive mechanisms for said shuttles actuating a shuttle in one loop of the guide way to completely traverse said loop while a shuttle is partially traversing the opposite loop.

37. In a wire bending machine, the combination of the coil forming pins; a shuttle 15 guide way in the form of a figure 8; a driving mechanism for each loop of the guide way; said driving mechanisms being timed to carry a shuttle completely through one 20 loop of the guide way and force it into the opposite loop while a companion shuttle is in the said opposite loop.

38. In a wire bending machine, the combination of two coil forming pins; a shuttle 25 guide way to form figure 8 coils arranged with relation to said pins; shuttles in said guide way; driving mechanism for said shuttles comprising rotative driving arms one for each loop, and one of said driving 30 arms having twice the speed of the other of said driving arms.

39. In a wire bending machine, the combination of coil forming pins; a figure 8 35 guide way arranged in relation to said pins to make a coil of figure 8 form thereon; a shuttle in said guide way; a driving mechanism for each loop of the guide-way, said driving mechanism being rotatively mounted and having a direction of movement to drive 40 the shuttle from one loop to the other in a downward direction.

40. In a wire bending machine, the combination of the coil forming pins; plate supports for said pins; a shuttle; a figure 8 45 guide way for said shuttle arranged with relation to said pins to carry a wire in said shuttle to form figure 8 coils on said pins; and raised deflectors 32 for the purpose described.

50. 41. In a wire bending machine, the combination of the coil forming pins; the plate supports for said pins; a shuttle; a figure-8 55 guide-way for said shuttle arranged with relation to said pins to carry wire in said shuttle to form figure 8 coils thereon; and the deflectors 33 extending from the plate to a point immediately adjacent to the pins toward the shuttle guides for guiding the wire to the base of the pins.

60. 42. In a wire bending machine, the combination of two coil forming pins; a shuttle; a figure 8 guide way for the shuttle arranged in relation to the pins to make a figure 8 coil thereon as the shuttle traverses 65 the guide; and means for adjusting the dis-

tance between the pins to vary the size of the coil.

43. In a wire bending machine, the combination of two coil forming pins; mechanism for coiling the wire in the form of a 70 figure 8 on said pins; and means for adjusting distance between said pins to vary the width of the coil.

44. In a wire bending machine, the combination of a coil forming pin; a shuttle 75 guide way arranged in relation to said pin to carry a wire in a shuttle in said guide way around the pin, said guide way being formed by a central plate and an outer plate; the central plate supporting the coil 80 forming pin; a shuttle in the guide way; and means for driving the shuttle.

45. In a wire bending machine, the combination of a coil forming pin; a shuttle 85 guide way arranged in relation to said pin to carry a wire in a shuttle in said guide way around the pin, said guide way being formed by a central plate and an outer plate, the central plate supporting the coil forming pin; a shaft for supporting the 90 central plate; a shuttle in the guide way; and a rotative shuttle driving mechanism mounted on the shaft.

46. In a wire bending machine, the combination of a coil forming pin; a shuttle 95 guide way comprising a central and outer plate; means for adjusting one plate with relation to the other; and means for driving the shuttle.

47. In a wire bending machine, the combination of a coil forming pin; a guide way 100 comprising a central plate and outer plate with an intervening space between said plates; a shaft supporting the center plate; means for adjusting the shaft laterally to 105 adjust the center plate relatively to the outer plate; and a shuttle in the guide way.

48. In a wire bending machine, the combination of a coil forming pin; a guide way 110 comprising a central plate and an outer plate with an intervening space between said plates; a shaft supporting the central plate; means for adjusting the shaft laterally to adjust the central plate relatively to the outer plate; and a driving mechanism 115 rotatively mounted on said shaft for driving said shuttle.

49. In a wire bending machine, the combination of two coil forming pins; a figure 120 8 guide way formed by an outer plate and two central plates having an intervening space between the plates; shafts supporting said central plates; a shuttle in the guide way; driving mechanisms rotatively mounted on said shafts, the driving mechanism for 125 one loop of the guide way being driven from the driving mechanism on the companion shaft.

50. In a wire bending machine, the combination of coil forming pins; a guide way in 130

- the form of a figure 8 and formed by two central plates, and an outer plate with an intervening space between them; shuttle-driving mechanisms on said shafts, and 5 gears journaled on said shafts for driving the shuttle-driving mechanisms.
51. In a wire bending machine, the combination of figure-8 coiling devices for forming a plurality of coils having common axes 10 lengthwise of the fabric; and flattening devices for flattening the fabric formed by said coils.
52. In a wire bending machine, the combination of figure-8 coiling devices for forming a plurality of coils having common axes 15 lengthwise of the fabric; and mechanisms intermittently engaging the fabric for flattening the same.
53. In a wire bending machine, the combination of two pins; means for carrying a wire over said pins to form a plurality of figure-8 coils having common axes lengthwise of the resulting fabric, and acting therewith for continuously forming the coils 20 on said pins; and a flattening device acting on the resulting fabric.
54. In a wire bending machine, the combination of figure 8 coiling-devices for forming coils with their axes lengthwise of the 25 fabric; and a flattening device for flattening the fabric formed of said coils.
55. In a wire bending machine, the combination of figure-8 coil-forming devices for forming coils with their axes lengthwise of 30 the fabric; and mechanism intermittently engaging the fabric for flattening the same.
56. In a wire bending machine, the combination of two pins; means for carrying a wire over said pins to form figure 8 coils 35 with the axes of the coils lengthwise of the resulting fabric and acting therewith for continuously forcing the coils forward on said pins; and a flattening device acting on the resulting fabric.
57. In a wire bending machine, the combination of two pins; mechanism acting with the pins for coiling a wire in the form of a figure 8 on said pins and continuously forcing the coil thus formed forward on the 40 pins; a guide way into which the coil thus formed is forced; and a flattening device acting on the fabric in the guide way.
58. In a wire bending machine, the combination of two pins; mechanism acting with the pins for coiling a wire in the form of a figure 8 on said pins and continuously forcing the coil thus formed forward on the pins; a guide way into which the coil thus formed is forced; and a flattening device 45 acting on the fabric in the guide way by intermittently engaging with the fabric.
59. In a wire bending machine, the combination of a figure-8 coil-forming device for forming coils with their axes lengthwise 50 of the resulting fabric; a flattening mech- anism operating upon the fabric thus formed; and a lengthening means operating upon the flattened fabric.
60. In a wire bending machine, the combination of forming devices arranged to 75 form a figure 8 coil, one coil being interlocked with another; a flattening mechanism; and a lengthening device operating upon the fabric thus formed.
61. In a wire bending machine, the combination of figure 8 coil forming devices for forming coils with their axes lengthwise of the resulting fabric; a flattening device; and a reciprocating lengthening device for 80 engaging and lengthening the fabric step by step.
62. In a wire bending machine, the combination of figure-8 coil-forming devices; a hammer for flattening the coil; a reciprocating lengthening mechanism; said reciprocating lengthening mechanism being timed with relation to the hammer to strain 85 the fabric while engaged by the hammer.
63. In a wire bending machine, the combination of figure-8 coil-forming devices for 90 forming coils with their axes lengthwise of the resulting fabric; a flattening mechanism and a hammer for operating upon the fabric, the hammer having a curved surface with the axis of curve across the fabric and parallel thereto.
64. In a wire bending machine, the combination of figure-8 coil-forming devices for 95 forming coils with their axes lengthwise of the resulting fabric; and means for crushing the fabric thus formed and setting it with greater concavity at one side than at the opposite side.
65. In a wire bending machine, the combination of figure-8 coil-forming devices; a 100 flattening mechanism for flattening the coil thus formed; and a hammer having a curved surface for giving a set to the fabric on a curve having its axis across the fabric and parallel thereto and having a surface for giving the fabric greater concavity at one side than at the opposite side.
66. In a wire bending machine, the combination of figure-8 coil-forming devices; a 105 guide into which the coil is forced having a movable side; means for reciprocating said side; and a hammer operating upon the coils in the guide.
67. In a wire bending machine, the combination of forms over which the wire may 110 be coiled with portions transverse to the resulting fabric; and means for coiling and shaping a plurality of wires on said forms and for twisting the transverse portions of the coiled fabric.
68. In a wire bending machine, the combination of forms over which the wire may 115 be coiled with portions transverse to the resulting fabric; and means for coiling and shaping a plurality of wires on said forms 120
69. In a wire bending machine, the combination of forms over which the wire may 125 be coiled with portions transverse to the resulting fabric; and means for coiling and shaping a plurality of wires on said forms 130

- and for twisting the transverse portions of the coiled fabric all in a direction to increase the twist as the fabric is flexed in one direction.
- 5 69. In a wire bending machine, the combination of forms over which the wire may be bent to serpentine form, forming oppositely disposed loops with portions transverse to the resulting fabric; and means for 10 coiling and shaping a plurality of wires on said forms and for twisting the transverse portions.
70. In a wire bending machine, the combination of two coil forming pins; means 15 acting on the pins for forming figure-8 coils with the axis of the coils lengthwise of the resulting fabric, said means being arranged to subject the transverse portions of the coil to an initial twist.
- 20 71. In a wire bending machine, the combination of two coil forming pins; and means acting with the pins for forming and associating a plurality of figure-8 coils with a plurality of wires on said pins, arranged to 25 subject the transverse portions of said coils to an initial twist.
72. In a wire bending machine, the combination of forms over which the wire may be coiled forming loops with portions transverse to the resulting fabric; and means for 30
- coiling a plurality of wires on said forms and for twisting the transverse portions with the loops formed in the different wires interlocked.
73. In a wire bending machine, the combination of forms over which the wire may be coiled forming loops with portions transverse to the resulting fabric; and means for coiling a plurality of wires on said forms and for twisting the transverse portions 35 with the loops formed in the different wires interlocked and only at one edge.
74. In a wire bending machine, the combination of forms over which the wire may be coiled with portions transverse to the resulting fabric; and means for coiling and shaping a plurality of wires on said forms and for twisting the transverse portions of the coiled fabric, all in directions tending to curl the resulting fabric in one direction; 40 and a hammer for giving the fabric a set in the reverse direction.

In testimony whereof I have hereunto set my hand in the presence of two subscribing witnesses.

JOHN R. DEAN.
